John Bollen Jun:

Sept. 29, 1804

Letter Patent Sept. 29, 1804.

The schedule appears to in this Letter Patent and making part of the same containing a description in the words of the said John Bollen Jun: himself of his Waggon or carriage to be worked by hand.

The Waggon is to be mounted with a crank which is to extend from one side to the other, with a wheel at each end, & these wheels to move the second, and the second the third, and the third to move a wheel which is to be nearly of the diameter of, and to be fastened to, the inside of the hind wheel of the carriage; and these hind wheels to be worked with iron bars or pins at the space of eighteen inches apart, to prevent it from slipping. The fore wheels are to be guided with an iron, which is to extend into the waggon to which it about, or to steer it in any direction.

Some or more information which may be need.

Witness,

John Lowell
Robert Harrison

John Bollen Jun:

172. 2. 29.

Delivered, made, B. 15. 1804.
